UNITED STATES PATENT OFFICE.

FRANCIS I. DU PONT, OF WILMINGTON, DELAWARE, ASSIGNOR TO THE E. DU PONT DE NEMOURS POWDER COMPANY, OF WILMINGTON, DELAWARE, A CORPORATION OF NEW JERSEY.

CARTRIDGE.

No. 838,748.

Specification of Letters Patent.

Patented Dec. 18, 1906.

Application filed August 2, 1905. Serial No. 272,290.

To all whom it may concern:

Be it known that I, FRANCIS I. DU PONT, a citizen of the United States, residing at Wilmington, county of Newcastle, and State of Delaware, have invented a new and useful Improvement in Cartridges, of which the following is a full, clear, and exact description, reference being had to the accompanying drawings, which form a part of this specification.

My invention relates to smokeless-powder cartridges.

The object of the invention is to ignite a charge of smokeless powder simultaneously at all points. To effect this object, I prepare a smokeless-powder charge in the form of a sheet and a priming charge of quick-burning material, also in the form of a sheet, and insert them into the shell. Preferably each charge is composed of a single sheet, and one sheet is superimposed on the other to form a compound sheet, which is coiled tightly in spiral form and inserted into the shell.

In the drawings, Figure 1 is a side elevation of a cartridge. Fig. 2 is a perspective view showing the charge in process of formation. Fig. 3 is a perspective view of the completed charge.

a represents the cartridge-shell, b the sheet of smokeless powder, and c the sheet of quick-

burning priming material. The priming charge may be formed of any suitable material; but I prefer to use cloth woven of gun-cotton.

While I prefer to have each cartridge contain but a single sheet of smokeless powder and a single sheet of priming material, there may be a plurality of sheets of each charge in a single shell. The sheets may be of equal size, although if but a single sheet of each charge be used to a shell the sheet should be of a size to practically fill the shell. While one sheet should be superimposed on the other, the sheets may or may not be attached together. While I prefer to coil the sheets spirally within the shell, the spiral arrangement is not essential.

Having now fully described my invention, what I claim, and desire to protect by Letters Patent, is—

An explosive charge for a gun consisting of a cloth woven of gun-cotton superimposed on a smokeless-powder charge in sheet form.

In testimony of which invention I have hereunto set my hand, at Wilmington, Delaware, on this 25th day of July, 1905.

FRANCIS I. DU PON
